ATTORNEY-

UNITED STATES PATENT OFFICE

92,066

DESIGN FOR A COMBINED INSTRUMENT PANEL FOR A MOTOR VEHICLE AND RADIO

Ray C. Ellis, Detroit, Mich., assignor to Radio
Corporation of America, a corporation of Dela-
ware

Application March 11, 1933, Serial No. 47,433

Term of patent 7 years

To all whom it may concern:

Be it known that I, RAY C. ELLIS, a citizen of United States of America, residing at Detroit, Michigan, have invented a new, original, and ornamental Design for a Combined Instrument Panel for a Motor Vehicle and Radio of which the following is a specification forming part thereof, in which:

The drawing is a front view of a combined instrument panel for a motor vehicle and radio showing my new design. It should be under-

stood that the loudspeaker grille and tuning dial window are substantially in the same plane as the instrument panel and that the control knobs of the radio set project outwardly from the instrument panel.

I claim:

The ornamental design for a combined instrument panel for a motor vehicle and radio as shown and described.

RAY C. ELLIS.
